(57) **CLAIM**

The ornamental design for a stand mixer, as shown and
described.

DESCRIPTION

FIG. 1 is a top-front perspective view of a stand mixer
showing our new design;

FIG. 2 is another top-front perspective view thereof;

FIG. 3 is a front elevation view thereof;

FIG. 4 is a rear elevation view thereof;

FIG. 5 is a right side elevation view thereof;

FIG. 6 is a left side elevation thereof;

FIG. 7 is a top plan view thereof;

FIG. 8 is a bottom plan view thereof;

FIG. 9 is a bottom-rear perspective view thereof;

FIG. 10 is a bottom-front perspective view thereof;

FIG. 11 is a top-front perspective view showing the stand
mixer in a raised position;

FIG. 12 is another top-front perspective view thereof;

FIG. 13 is a front elevation view thereof;

FIG. 14 is a rear elevation view thereof;

FIG. 15 is a right side elevation view thereof;

FIG. 16 is a left side elevation thereof;

FIG. 17 is a top plan view thereof;

FIG. 18 is a bottom plan view thereof;

FIG. 19 is a bottom-rear perspective view thereof; and,

FIG. 20 is a bottom-front perspective view thereof.

The dashed broken lines in the figures illustrate portions of
the stand mixer that form no part of the claimed design.

1 Claim, 19 Drawing Sheets
